FRED H. WHITE, OF CHARLOTTE, NORTH CAROLINA.

STRIPPING, ETC., EQUIPMENT OF TEXTILE MANUFACTURING PLANTS.

Application filed March 12, 1926. Serial No. 94,171.

Heretofore in many cases a textile manufacturing plant has been furnished with a card-stripping equipment including a piping system through which the stripings are transported pneumatically, and a receiver in conjunction with such system into which the stripings are carried by the air flowing through the piping system, and within which the fibrous material is retained and collected. The equipment aforesaid has great practical merit by reason of the saving of labor in stripping, and of the efficiency with which the stripings are taken care of as the stripping operation proceeds, as well as of the convenience with which they are transported to a place where they may be collectively taken care of. As constituted prior to the present invention, however, the said equipment has the drawback that the stripings from all of the carding engines which are served by the equipment are received within one and the said receiver. Consequently, in practice, the stripings from various carding engines become mixed in the one receiver, unless the latter is emptied of its contents as often as may be required in order to avoid such mixing. This entails various disadvantages and some inconvenience. For example, in some mills the carding engines of a mill are employed in groups for carding stocks of different colors, grades, or kinds. All of the different groups being served by the same pneumatic system, it follows that if the latter, as heretofore, delivers the stripings of all of the different sorts of stock to a single receiver, and if stripings of different sorts, for example stripings of different grades or colors, are delivered together into such receiver, it frequently will be the case that the mixing which results detracts from the quality and value of the contents of the receiver, or from its availability for particular uses, or necessitates special after-treatment. If, in order to avoid mixing, the receiver is cleaned out after the last carding engine of the group operating upon one sort of stock has been stripped, before beginning to strip the first carding engine of a group operating upon a different sort, the cleaning-out entails more or less interruption and delay between the stripping of one group and that of the next, and sometimes more or less inconvenience, especially if the same sort of stock is being operated upon by scattered groups of carding engines. The present invention obviates these and other disadvantages of equipment having a single receiver. In addition, it serves new and important practical purposes, whereby it materially extends the range of usefulness of the equipment in which it is incorporated. One important result attained by the invention is that of providing in convenient and advantageous manner for keeping card stripings of different sorts of stock distinct; that is to say, avoiding the mixing together of stripings of different colors, grades, and kinds of stock. Another, is that of rendering it unnecessary, after having finished stripping the carding engines which are employed in the carding of one sort of stock, to delay until after the stripings from such carding engines have been removed from the receiver in which they were collected, before beginning to strip a group of carding engines employed in the carding of another sort of stock, as has been necessary in the case of the single receiver systems heretofore in use. Another important result attained by the invention is that, by reason of enabling different sorts of materials passed through the pneumatic piping system to be segregated and disposed of separately, the invention renders it practicable to employ a pneumatic card-stripping system either for its primary purpose of card-stripping, or for taking up various kinds of wastes or by-products, or for cleaning flyings, etc., from machinery and floors, with facility in keeping the different kinds or grades of pneumatically transported material separate and distinct, and without the value and quality of the higher grades of material being affected injuriously through admixture of inferior grades or dirt therewith. The main phase of the invention provides, in combination with the pneumatic system of piping aforesaid, serving as a conduit through which stripings, etc., from a plurality of machines are transported by flow of air, a plurality of receivers, means for reducing air-pressure to induce flow of air through the piping, and means adjacent the said receivers for selectively and interchangeably establishing and disestablishing flow from the said pneumatic piping system into either of the said receivers, at will. This combination enables admixture of the transported material to be avoided, by reason of enabling either of the receivers to be made the working receiver at will, and thereby enabling the material to be collected

in whichever receiver it is desired should contain it. The invention facilitates the attainment of the desired results in this respect by reason of containing provision for 5 converting a reserve receiver into the working receiver, and discontinuing the flow of strippings or the like into the receiver which previously was the working one, without the inconvenience of cleaning out a 10 working receiver because of the change in order to enable it to be continued in use following the change, and without the delay incident to the work of cleaning out. The invention includes, further, combinations 15 and features which are pointed out in the claims at the close of this specification.

An illustrative embodiment of the invention is shown in the drawings, in which latter,—

20 Fig. 1 is a view showing the main elements of such embodiment in side elevation, with flooring and some piping in vertical section.

25 Fig. 2 is a view thereof looking from the left in Fig. 1.

Fig. 3 is a plan view of the same, with some parts and flooring omitted.

30 Fig. 4 is a detail view, on a larger scale, showing in vertical section the mouth-end 35 of one of the intake-pipes connected with the receivers to which reference is made herein-after, and the closure for said mouth-end, with the said closure sealed upon the mouth and thereby sealing the latter.

35 Fig. 5 is a plan view of the parts that are shown in Fig. 4, with small portions broken away.

40 Fig. 6 is a view partly in side elevation and partly sectional showing the parts of Figs. 4 and 5, with the closure-device thrown back, and with the addition of a coupling-piece applied to the mouth of the intake, and of a portion of a section of armored flexible piping combined with said coupling-piece.

45 Having reference to the drawings:

50 Figs. 1, 2 and 3 indicate in dotted lines machines in connection with which stripping or cleaning operations are to be performed, which machines may be conceived to 55 be carding engines, although in various cases in practice the principles of the invention are applied in connection with other machines and are utilized for other or additional purposes. Certain portions of the piping of a pneumatic system are indicated at 1, 1. Such piping in practice is disposed in convenient relations with respect to the machines it serves, and is connected up with attachments, appliances, etc., for stripping, 60 cleaning, etc., according to the work to be performed, throughout the required field of operation. Ordinarily a system of this class takes care of a large number of machines.

65 At 2, 2, Figs. 1, 2, 3, are partly represented intake connections in the shape of flexible

70 pipes which are capable of being connected with card-stripping devices, cleaner nozzles, etc. The piping and these intake connections are distributed in various places throughout a mill, with sometimes such connections provided in conjunction with individual machines, and usually supplemental ones also.

75 The plurality of receivers which, in accordance with the invention, is provided for selective reception of the material which is transported through the piping system by the flow of air, comprises in the drawings a battery of seven receivers, 7, 7, etc., and 6. The number of receivers comprised in the 80 plurality, is optional and in practice varies according to the number of sorts of material transported and required to be segregated. Seven receivers having connections, etc., such as those which are shown in the drawings, will enable any number of different sorts of fibrous material up to seven to be segregated through being collected separately in the respective receivers, as for example strippings of seven different colors, 85 or strippings of a smaller number of colors, and waste, etc., of several different sorts.

90 The provisions for producing a flow of air and material through the piping 1 and into the selected receiver may vary in practice 95 from what is shown in the drawings, in carrying the broader phases of the invention into effect. It is to be understood, however, that what is shown includes a number of the 100 more specific features of the invention which are set forth in the claims. The drawings show, as a portion of the said provisions, means for reducing air-pressure to induce flow of air through the piping, such means constituted by a pump 11, the said pump 105 having convenient connections between it and the receivers 7, 7, 6, for enabling air to be withdrawn by the pump from the collecting chambers of the receivers and thereby inducing flow of air and material, such as 110 strippings, through piping 1 when the latter is connected up with one of the receivers. Such connections between the receivers and the pump in this instance comprise elbows 115 48, 48, Fig. 2, combined with the domes 43, 43, of receivers 7, 7, short pipe-sections 82, 82, engaged with said elbows, a trunk-pipe 8 with which the receivers 7, 7, are connected in pairs by means of the said elbows and short pipe-sections, an elbow 26 combined 120 with the dome 22 of receiver 6, a short pipe-section 81 engaged with said elbow, a pipe 9 that is engaged at its upper end with pipes 8, 81, and at its lower end is in communication by an elbow 29 with a filter-chamber 6^a 125 at the base of receiver 6, and a pipe 10 communicating at one end thereof with the space at the interior of a filter 42 within the said filter-chamber and at the other end thereof with the pump. As will be apparent, when 130

the pump 11 is in operation it will reduce the air-pressure within the connections and the receivers and filter-chamber by exhausting the air therefrom.

- 5 The means for selectively establishing working communication between the piping 1 and either of the receivers as may be necessary may be varied, without exceeding the scope of the invention. In the illustrated 10 embodiment of the principles of the invention each of the receivers has associated therewith an intake-pipe 5 having a mouth 4. The intake-pipes 5, 5, are arranged with their mouths in a group, the members of the 15 group being so disposed that the mouth 4 of any one of the intake-pipes may be reached and engaged by a coupling-piece 12, Figs. 1, 2 and 6, on the free end of a section 3 of flexible pipe in connection with a pipe-section 1^a with which the various branches of the piping are in communication. The point at which the flexible connecting-section is located in connection with the piping system may be regarded as a distributing point 20 which in practical effect is central as regards the different receivers. In Fig. 1 the flexible connecting-section 3 is disconnected from all the intakes. It may at will be connected as in Fig. 6 with any one of the mouths 4, thereby placing the piping 1 in communication with the corresponding receiver. By 30 disconnection of the flexible connecting-system from such mouth, and reconnection with another mouth, communication between the 35 piping 1 and the said receiver may be disestablished and working communication between the said piping and the receiver corresponding with the latter mouth may be established.
- 40 It will be understood that the collecting chambers of the various receivers, and the filter-chamber of receiver 6, are air-tight apart from their relations with the intake-pipes 5, 5, and pipe 9, respectively, so that 45 when internal air-pressure therein is lowered or reduced, there is an effective tendency to flow of air into the receivers and filter-chamber through the respective pipes. Provision is made for stopping the flow of 50 air through the idle receivers by means of valves. These may be located at points suitable for the purpose between the respective receivers and the pump, or may be applied in connection with the intake-pipes 5, 5, etc., 55 or in both relations, as may be deemed advisable. In the illustrated embodiment, the valves are applied at the mouths 4, 4, of the said intake-pipes. In this instance, the said mouths are located, for convenience, at the 60 extreme ends of the intake-pipes, as indicated best in Figs. 4, 5 and 6, and each of the valves for such mouth is constituted by a cover 15 provided with packing 18 to fit against the rim of the corresponding mouth. 65 Each valve is loosely hinged by means of a
- pin 14, carried by a lateral projection from the valve, to an upstanding arm 131 of a mounting constituted by a ring 13 surrounding the mouth-end of the corresponding intake-pipe and made fast therewith by means 70 of clamping screws 132, 132. When an intake-mouth is closed by its valve, as in Figs. 4 and 5, the reduction of the internal air-pressure within the intake and corresponding receiver causes the valve to be held 75 closely against the seat of the intake-mouth by the external atmospheric pressure. For the convenient manipulation of the valves, each cover is furnished with a projecting handle 151 of sufficient length to afford 80 effective leverage to overcome external atmospheric pressure in separating the valve from its seat around the mouth of the intake-pipe. The packing 18 is held to the under side of the cover 15 by means of a 85 disk 17 which is secured to the cover by a central bolt 16. The disk 17 has a beveled edge to facilitate the entrance of the disk into the intake-pipe mouth 4, which it fits somewhat closely, and in the present instance, in order to assist in centering the packing 18, such packing is in the form of a 90 annulus which receives within its central opening a central raised boss on the disk 17. This boss, by contacting with the under side of the cover 15 prevents the packing from being injured or distorted as a result of undue compression between the disk and the cover as a result of tightening bolt 13. To enable the valve to accommodate 95 itself readily to the mouth 4 with which it cooperates, its hinge-connection with its mounting is made a loose one through vertical elongation of the hole 141 (in arm 131 of ring 13) occupied by the hinge-pin 14. 100
- The coupling-member 12 at the lower end of flexible connecting-pipe 3 is tubular and its engaging portion fits over the mouth-end of the intake-pipe to which it is applied. To prevent leakage of air inward between 105 said engaging portion and said mouth-end, packing 19 is applied to the upper side of ring 13, aforesaid. The said packing is in this instance held in place upon the ring by means of a metal ferrule 20 that surrounds 110 the ring and which is held in place by means of the clamping screws 132, 132, aforesaid, by which the ring is held in fixed position upon the intake-pipe mouth-end. The coupling-member is pushed home upon the 115 mouth-end of the intake-pipe until the lower edge of said member contacts with packing 19.
- The upper end of flexible connecting-pipe 3 is shown in Fig. 6 as provided with a 120 screw-threaded coupling-sleeve 35 by means of which to connect said end with the portion 1^a of the piping 1.
- The pump 11 when at work reduces the 125 air-pressure throughout the whole system 130

of receivers and their associated connections. In the case of those receivers having their intake-mouths 4, 4, closed by means of their valves 15, no flow of air through such receivers takes place. In the case, however, of that receiver, which for the time being has its intake-mouth connected by means of the flexible pipe 3 with the system of piping 1, flow of air takes place through the piping 1 to and through the said receiver, depositing in the latter the coarser elements of its load of transported material, and from such receiver the air passes through the filter-chamber and filter to the pump 11, leaving the fine elements of said material, such as dust, behind within the filter. A single filter-chamber and filter are all that is required in the case of the illustrated equipment, inasmuch as the described connections place the collecting chambers of all of the receivers in communication with the filter-chamber, and only one collecting chamber is in use at a time. Such filter-chamber and filter are for convenience and economy of construction built in, so to speak, with receiver 6, as portions thereof adjunctive to the collecting chamber of the said receiver.

The capacity of the coupling-piece 12 to be shifted readily from the mouth of one intake-pipe to that of another renders it possible to switch the flow of air and its burden of strippings or the like easily and instantly from one receiver to another.

In operation, for instance in connection with a number of carding engines, the individual receivers 7, 7, 6, in every instance may be utilized to receive only one particular color (or other sort) of strippings or the like passing through the piping system 1, or if desired the receiver 6 may be utilized to receive strippings from all the carding engines when it is not desired to segregate strippings from the several machines. Any one of the receivers 7 may be utilized for this latter purpose if circumstances render it convenient to thus utilize it.

What is claimed as the invention is:—

1. A pneumatic card-stripping, or the like, equipment comprising, in combination, a pneumatic piping system through which strippings, etc., from a plurality of machines are transported by flow of air, a plurality of receivers, pressure-reducing means, and means adjacent the said receivers for selectively and interchangeably establishing working communication between the terminal portions of the said pneumatic piping system and the pressure-reducing means through either of said receivers, at will.

2. A pneumatic card-stripping, or the like, equipment comprising, in combination, a pneumatic piping system through which strippings, etc., from a plurality of machines are transported by flow of air, a plurality of receivers, means for reducing air-pressure to

induce flow of air through the piping, and means adjacent the receivers for selectively and interchangeably establishing working communication between the terminal portion of the said pneumatic piping system and either of said receivers, at will. 70

3. A pneumatic card-stripping, or the like, equipment comprising, in combination, a pneumatic piping system, a plurality of receivers, means adjacent the said receivers for selectively and interchangeably establishing working communication between the terminal portion of such piping system and either of said receivers as required, and a single pressure-reducing means connected with said receivers collectively, whereby through the selected receiver pressure may be reduced in the piping system with resulting flow of air through the said system and delivery of air-transported material within such receiver. 80

4. A pneumatic card-stripping, or the like, equipment comprising, in combination, a pneumatic piping system through which strippings, etc., are transported by flow of air, a plurality of receivers, means for reducing air-pressure within the receivers, and means adjacent the receivers for selectively and interchangeably establishing working communication between the terminal portion of the said pneumatic piping system and either of said receivers at will. 90

5. A pneumatic card-stripping, or the like, equipment comprising, in combination, a pneumatic piping system through which strippings, etc., from a plurality of machines are transported by flow of air, a plurality of receivers, means for reducing air-pressure to induce flow of air through the piping, and means adjacent the receivers for selectively and interchangeably establishing and disestablishing flow from the said pneumatic piping system into either of the said receivers, at will. 100

6. A pneumatic card-stripping, or the like, equipment comprising, in combination, a pneumatic conduit through which strippings, etc., from a plurality of machines are transported by flow of air, a series of air-tight receivers, means for exhausting the air from the said receivers, and means adjacent the receivers for selectively placing the said pneumatic conduit in interchangeable communication with the respective receivers. 110

7. A pneumatic card-stripping, or the like, equipment comprising, in combination, a pneumatic conduit through which strippings, etc., are transported by flow of air, a series of air-tight receivers, means for exhausting air from the interior of said receivers, intakes for the respective receivers, and means for selectively placing the conduit in connection with the respective intakes. 120

8. A pneumatic card-stripping, or the like, equipment comprising, in combination, 130

a pneumatic conduit through which stripings, etc., are transported by flow of air, a series of receivers, a filter, intakes for the respective receivers, means for selectively placing the conduit in connection with the respective intakes, and means for exhausting air from the working receiver and through the filter.

9. A pneumatic card-stripping, or the like, equipment comprising, in combination, a pneumatic conduit through which stripings, etc., are transported by flow of air, a series of air-tight receivers, intakes for the respective receivers having air-tight closure means operable to open and close said intakes, and means for selectively placing the said pneumatic conduit in interchangeable communication with the respective intakes.

10. A pneumatic card-stripping, or the like, equipment comprising, in combination, a pneumatic conduit through which stripings, etc., are transported by flow of air, a series of air-tight receivers, means for exhausting air from the said receivers, intakes for the respective receivers, and a flexible connection joined to the pneumatic conduit and adapted to be connected to the intakes of the respective receivers, interchangeably.

11. A pneumatic card-stripping, or the like, equipment comprising, in combination, a pneumatic conduit through which stripings, etc., are transported by flow of air, a series of receivers, each having a collecting chamber and one thereof having in addition a filter-chamber and filter, means for selectively placing the said pneumatic conduit in interchangeable communication with the respective collecting chambers, means through which all of said collecting chambers communicate with the filter-chamber, and means for exhausting air from the filter-chamber through the filter.

12. A pneumatic card-stripping, or the like, equipment comprising, in combination, a pneumatic conduit through which stripings, etc., are transported by flow of air, a series of air-tight receivers, means for exhausting air from the said receivers, intakes for the respective receivers having closure devices which are held to their seats by external air-pressure, and are operable at will to open and close said intakes, and a coupling-member for selectively placing the said pneumatic conduit in interchangeable communication with the respective intakes.

FRED H. WHITE.
